UNITED STATES PATENT OFFICE.

RALPH I. FROST, OF AUGUSTA, KANSAS, ASSIGNOR TO THE GEO. W. BROWN & SON STATE BANK, TRUSTEE, OF AUGUSTA, KANSAS.

DESIGN FOR A CASING FOR AN ELECTRICAL GENERATOR.

58,560.

Specification for Design.

Patented Aug. 2, 1921.

Application filed December 6, 1920. Serial No. 428,828. Term of patent 14 years.

To all whom it may concern:

Be it known that I, RALPH I. FROST, a citizen of the United States, residing at Augusta, in the county of Butler and State of Kansas, have invented a new, original, and ornamental Design for a Casing for Electrical Generators, of which the following is a specification, reference being had to

the accompanying drawing, forming part thereof.

Figure 1 is a side elevation of my new design, Fig. 2 is a top view of the same.

What I claim is,

The ornamental design for a casing for an electrical generator as shown.

RALPH I. FROST.
